TYPEWRITER RULING DEVICE

Abram Lvovich Goldberg and Vladimir Grigorevich Dauman, Harbin, Manchuria, China, assignors to Lew Zilkman, Harbin, Manchuria

Application July 14, 1934, Serial No. 735,119½

6 Claims. (CL 197—113)

This invention relates to typewriting machines, and its general object is to provide a line ruling device that can be attached to practically all makes of typewriters now in general use, in an easy and expeditious manner, and for use in drawing or ruling straight, accurate, clear and distinct horizontal or vertical lines, merely by moving the carriage of the typewriter, for horizontal lines and rotating the platen for vertical lines, after slight manipulation of the parts is made, therefore it will be seen that the lines can be drawn with very little effort on the part of the operator.

A further object of the invention is to provide a line ruling device that is movable for disposal in operative or idle positions, and when in the latter position will in no way interfere with the use of the typewriter in letter writing and the like, and in fact, our device can be used alternately with the type in writing and line drawing on the same sheet or sheets without changing their position or removing the same from the machine.

Another object of the invention is to provide a line ruling device that will in no way damage the platen or other parts of the machine, even after long usage, as pounding action is eliminated by the use of our device, as distinguished from the use of the hyphen and dash type bars now generally employed for line drawing.

A still further object of the invention is to provide a line ruling device that includes means to exert pressure on the line drawing wheels and which is adjustable in accordance with the number or thickness of the sheets to be lined, whereby lines drawn on carbon copies will be clear and distinct.

Another object of the invention is to provide a line ruling device in the form of an attachment for a typewriting machine, that is simple in construction, inexpensive to manufacture and extremely efficient in operation, use and service.

This invention also consists in certain other features of construction and in the combination and arrangement of the several parts, to be hereinafter fully described, illustrated in the accompanying drawing and specifically pointed out in the appended claims.

In describing our invention in detail, reference will be had to the accompanying drawing wherein like characters denote like or corresponding parts throughout the several views, and in which:—

Figure 1 is a front view of the line ruling device which forms the subject matter of the present invention.

Figure 2 is a rear view thereof.

Figure 3 is a side elevation.

Figure 4 is a top plan view showing the device in operative position.

Figure 5 is a similar view with the device in idle or inoperative position.

Figure 6 is a detail view of the wheel carrying and inking cylinder.

Figure 7 is a perspective view of the pivot shaft.

Figure 8 is a similar view of the cam disk.

Referring to the drawing in detail, the reference numeral 1 indicates the attaching plate of our type-bar guide, which includes an upright 2 having a tapered face and which is vertically slit or recessed as at 3 for the passage of the guide 15 stems on the type heads of the type bars. In applying our device to a typewriter, the type bar guide thereon is removed and our guide substituted therefor.

The upright has formed on the upper end thereof and extending forwardly therefrom a pair of guide members 4 and 5 extending from opposite sides of the recess as best shown in Figure 5, and the guide member 5 is in the form of a bracket, in that it is provided with an enlarged flat outer end 6 to act as an attaching and supporting means for parts which will be presently described.

The enlarged guide member or bracket 5 has a curved front edge and a square cornered opening therethrough adjacent its outer end, for the purpose of receiving the square cornered portion 7 of a shaft 8, whereby the shaft will be held fixed and against rotation with respect to the bracket 5, through the instrumentality of a nut 9 threaded to the lower threaded portion of the shaft, as will be apparent upon inspection of Figure 7, the nut contacting the under surface of the bracket as shown in Figure 1.

The shaft 8 has formed thereon just above the square cornered portion, an enlarged rounded portion 10 that has pivotally mounted thereon, an arm 11 that extends laterally from the lower end of a body member 12 and extending from the body member in opposed relation with respect to the arm 11 is a handle 13, the latter having a serrated outer end or finger gripping portion 14.

The body member 12 has formed thereon superimposed apertured lugs 15 to receive a screw bolt 16 mounted for rotation therein and threaded on the screw bolt 16 are lugs 17 which extend from a cylinder 18, consequently, it will be seen that the cylinder is carried by the handled body member to be moved therewith, and the cylinder is capable of vertical movement through the instru-

mentality of the screw bolt 18 and for a purpose which will be later apparent.

Formed on the cylinder are ears 19 arranged in cooperating pairs and the pairs are superimposed as well as disposed at right angles with respect to each other, as best shown in Figure 3. Journalized between the ears of each pair is a line drawing wheel 20, and by disposing the pairs of ears at right angles with respect to each other, it will be seen that the wheels are arranged accordingly. The wheels extend into the cylinder which has an inking wick 21 therein, and the cylinder has an open upper end which is closed by a pivoted cover plate 22.

Depending from the cylinder is a guide stud 23 mounted for disposal between the guide members and to ride along the curved forward edge of the guide member or bracket 5, as will be apparent upon inspection of Figures 1 and 5. The guide stem is held accordingly through the instrumentation of a coil spring 24 having its end convolutions extended outwardly to contact the cylinder and the handle 13.

From the foregoing, it will be seen that the cylinder carries the wheels for movement to an operative position, as shown in Figure 4 or to an idle or inoperative position of Figure 5 by movement of the handle 13, and in order to hold the wheels in either of these positions, against casual movement, we employ a spring pressed cam means which includes a collar 25 having a square cornered opening therethrough to fit the square cornered portion 26 of the shaft 8, and the shaft has formed thereon a disk 27 provided with diametrically opposed recesses 28 for the passage of cam members 29 therethrough for disposal in depressions 30 arranged in the enlarged outer end of the arm 11, the cam members being formed on and depending from the collar 25, and having triangular shaped lower end portions to fit within the depressions which are shaped accordingly for that purpose.

The shaft terminates at its upper end into a threaded portion to receive a nut 31 and mounted on the collar 25 is a washer 32 which acts as an abutment means for the lower convolution of a coil spring 33 that has its upper convolution engaging the nut 31, whereby the pressure of the spring 33 can be regulated as will be apparent.

In view of the fact that the shaft 8 and collar 25 are held against rotation, and the arm 11 is mounted for rotation on the shaft, it will be obvious that the cam members ride into and out of the depressions 30, and are received therein when the wheels are in operative position as shown in Figure 4, consequently pressure will be exerted against the wheels, and this pressure is increased in accordance with the number and thickness of sheets within the typewriter, wherefore our line ruling device is not only capable of drawing horizontal and vertical lines on a single sheet but also can impress lines on a maximum number of carbon sheets.

In order to draw a horizontal line by our device, the wheels are disposed to the position as shown in Figure 4 and the carriage of the typewriter is then moved longitudinally in either direction. However when it is desired to draw vertical lines, the shift key is operated which lifts the platen on some typewriters and lowers the type bar guide on others. In any event, the horizontally disposed wheel is moved out of operative position and the vertical wheel is arranged for use, then the platen is rotated for moving the

sheet or sheets against the vertical wheel so that the vertical wheel can act thereon for drawing its lines accordingly.

It is thought from the foregoing description that the advantages and novel features of our invention will be readily apparent.

We desire it to be understood that we may make changes in the construction and in the combination and arrangement of the several parts, provided that such changes fall within the scope of the appended claims.

We claim:

1. An attachment for a typewriter comprising a pair of line drawing wheels disposed at right angles with respect to each other for use in drawing either vertical or horizontal lines, means carrying said wheels and pivotally connected to the type bar guide of the typewriter to be guided between the parts thereof, means for holding the wheel carrying means with the wheels in either an operative or inoperative position with respect to the guide, adjustable spring pressed cam means included in the holding means for urging the wheels to operative position and inking means for said wheels and included in the wheel carrying means.

2. A line drawing attachment for a typewriter comprising a cylinder, ears projecting from said cylinder and arranged in pairs disposed at right angles with respect to each other, wheels journaled between companion ears and extending into the cylinder, inking means in said cylinder and arranged in the path of the wheels, spring pressed means for pivotally securing the cylinder to the type bar guide of the typewriter, whereby said attachment can be disposed into and out of operative position and means for adjusting the height of the wheels.

3. A line drawing attachment for a typewriter comprising a cylinder, ears projecting from said cylinder and arranged in pairs disposed at right angles with respect to each other, wheels journaled between companion ears and extending into the cylinder, inking means in said cylinder and arranged in the path of the wheels, handled means carrying the cylinder, spring pressed means pivotally securing the handled means to the type bar guide of the typewriter whereby to allow movement of the cylinder for disposing the wheels into and out of operative position by the handled means and to hold the wheels accordingly, and means for adjusting the height of the cylinder and carried by the handled means.

4. A line drawing attachment for a typewriter, comprising a cylinder, ears projecting from said cylinder and arranged in pairs disposed at right angles with respect to each other, wheels journaled between companion ears and extending into the cylinder, inking means in said cylinder and arranged in the path of the wheels, handled means, cooperating lugs extending from the cylinder and the handled means, means received by the cooperating lugs for securing the cylinder to the handled means and for adjusting the height of the cylinder, and spring pressed means for pivotally securing the handled means to the type bar guide of the typewriter whereby said wheels can be disposed into and out of operative position by moving the cylinder accordingly through the medium of the handled means and held accordingly.

5. An attachment for a typewriter comprising a type bar guide, an extension on said guide, a cylinder, a pair of line drawing wheels carried by said cylinder and disposed at right angles with

- respect to each other for use in drawing either vertical or horizontal lines, inking means for said wheels and disposed in said cylinder, handled means carrying said cylinder and pivotally secured to the extension for moving the wheels into and out of operative position with respect to the type bar guide, and threaded means for adjusting the height of the wheels through the medium of the cylinder.
- 5 6. A line drawing device for a typewriter comprising a type bar guide including guide members, an enlarged flat outer end portion for one of said members and the latter having a curved edge, handled means pivotally secured to the outer end portion, a pair of line drawing wheels
- disposed at right angles to each other, means carrying the wheels and including inking means therefor and mounted for adjustment on the handled means, a guide stud for the wheel carrying means and arranged for movement on the curved edge to be guided between and out of the guide members, spring means for holding the stud against said edge, and adjustable spring pressed cam means for holding the wheel carrying means with the wheels thereof in either operative or idle positions and for urging the same to an operative position when moved accordingly by the handled means.
